UNITED STATES PATENT OFFICE.

JOSEPH HOLLIDAY CUTLIFF, OF MACON, GEORGIA.

HAME-FASTENER.

SPECIFICATION forming part of Letters Patent No. 639,535, dated December 19, 1899.

Application filed July 29, 1898. Serial No. 687,177. (No model.)

To all whom it may concern:

Be it known that I, JOSEPH HOLLIDAY CUTLIFF, a citizen of the United States, residing at Macon, in the county of Bibb and State of Georgia, have invented certain new and useful Improvements in Hame-Fasteners; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in hame-fasteners, and especially to a new and improved means whereby the ends of the hames may be quickly and easily locked together and detached, the ends 20 being held together by means of ratchet-teeth and a spring-pawl, means being provided for guarding against the pawl's being released and also for relieving the spring-pawl of pressure or strain that might come upon the same.

25 More specifically, the invention consists in providing, in connection with the ratchet-bar and hollow shell, a spring-pawl with wedge-shaped tooth-engaging end, said pawl being so mounted on the hollow shell as to have a 30 slight sliding longitudinal movement thereon, while near the free end of the pawl, on the outer circumference of the shell, is a loop designed to protect the spring-pawl.

To these ends and to such others as the invention may pertain the same consists, further, in the novel construction and adaptation of the parts, as will be hereinafter more fully described and then specifically defined in the appended claims.

40 My invention is clearly illustrated in the accompanying drawings, which, with the letters of reference marked thereon, form a part of this application, and in which drawings—

Figure 1 is a perspective view of my improved hame-fastening. Fig. 2 is a central longitudinal section through the fasteners when locked together. Fig. 3 is a detail view of the hollow shell, showing the sliding spring-pawl secured thereto.

45 Reference now being had to the details of the drawings, A designates a curved ratchet-rod to one end of which a hame is to be at-

tached, and its other end is beveled, so as to allow of its readily entering the hollow shell B, which is to be attached to one end of a 55 hame in the usual manner. This hollow shell is slightly curved, as illustrated, to conform to the shape of the curved ratchet-rod. Mounted on the circumference of the shell is the spring-pawl D, which is held to the shell by means of 60 a bolt E, passed through the wall of the shell and through an elongated slot F in said pawl. A portion of said pawl is bent at substantially right angles to the length of the pawl and is preferably slightly wedge-shaped, as 65 illustrated, for the purpose of making its hold against the teeth of the ratchet-rod as secure as possible. This bent and wedge-shaped end of the pawl rests normally in a transverse recess G in said shell and in the path of the 70 ratchet-rod, so that as the rod is forced into the end of the shell the beveled end of said rod will contact against the under edge of the wedge-shaped end of the pawl and the latter will be forced up, and the resiliency 75 of the pawl will cause its end to spring back into a notch or tooth of the rod. As the end of the ratchet-rod is inserted in the shell and comes in contact with the lug on the pawl the latter is forced slightly longitudinally until the lug strikes against the edge of the recessed portion, which limits its 80 movement in one direction, after which the free end of the pawl will rise and allow the end of the ratchet-rod to pass on, the pawl 85 engaging with one of the notches of the ratchet-rod, thus locking the rod to the shell. When there is any pulling strain on the ends of the hame, the ratchet-rod will engage against the lug on the pawl and draw it 90 slightly longitudinally in the opposite direction until the opposite side of the pawl-lug strikes against the edge of the recessed portion nearest the end of the shell in which the ratchet-rod first enters and can move no further, and any strain which might otherwise 95 come upon the pin E will be transferred to the lug on the pawl, which bears against the edge of the recess when there is a strain on the connecting parts. In order to release the 100 rod from the pawl, it will be necessary to raise the free end of the pawl from its engaging notch or tooth. On the surface of the said shell is a loop H, which is located adjacent to

the recess in which the wedge-shaped end of the pawl engages, as illustrated, and struck up from the pawl is a strip K, which is bent forward and extends through the loop H, 5 which serves as a guide for the extension and prevents a lateral movement of the free end of the pawl, as well as limiting its upward throw.

From the foregoing it will be seen that the 10 hame may be easily and quickly adjusted to different-sized collars, the pawl prevented from injury by reason of the loop, and owing to the slight sliding movement which is allowed the pawl will prevent any pressure 15 coming upon the latter.

Having thus described my invention, what I claim to be new, and desire to secure by Letters Patent, is—

1. A fastener for hames, comprising in combination the ratchet-rod, the hollow shell to receive said rod, a spring-pawl secured to the shell and having a bent end resting in a recess

in the shell and in the path of the ratchet-rod, said pawl having a slight sliding longitudinal movement, and a guide for its free 25 end, as set forth.

2. In a hame-fastener, the combination with the ratchet-rod and shell to receive same, of the spring-pawl having an elongated slot and headed pin passed through said slot and secured to the shell, the wedge-shaped teeth-engaging portion of the pawl adapted to have a slight longitudinal play in a recess in the shell, and a struck-up portion of the pawl extending into a loop on the shell, designed to 30 35 guide the pawl in its longitudinal and vertical movements, as shown and described.

In testimony whereof I affix my signature in presence of two witnesses.

JOSEPH HOLLIDAY CUTLIFF.
